UNITED STATES PATENT OFFICE

ARTHUR J. THERRIEN, OF NORTHBROOK, ILLINOIS, ASSIGNOR TO NATIONAL BRICK COMPANY, OF CHICAGO, ILLINOIS, A CORPORATION OF ILLINOIS

METHOD OF FORMING BRICKKILNS

Application filed May 28, 1928, Serial No. 281,018. Renewed July 7, 1930.

The present invention relates to the manufacture of brick, and while the invention herein described in detail relates to the manufacture of common building bricks, the invention is not limited to any particular grade of brick.

The present application discloses a continuation of some of the subject matter disclosed in my prior application, Serial No. 83,342, filed January 23rd, 1926, and also certain improvements over the methods described therein.

The bricks are hacked onto drying cars, in piles, and then placed in a suitable oven or dryer.

When the piles have passed through the dryer and been consolidated and taken up by the fork, they are then placed in position in the kiln, and the kiln is built up with arches of green brick of a single brick-length in width extending from side to side of the kiln. The kiln is scoved in any preferred manner, as for example, by smearing over the surface along the sides and ends a mixture of brick dust and water, or brick dust clay and water, burners are inserted at each end of each arch and burning is then begun. Preferably, but not necessarily dog houses or small tubular extensions of the arches formed of burned bricks are employed so as to bring the fire from the burner nozzles out nearer to the outside surface of the kiln. Obviously, removable scoving having suitable restricted openings for communicating with the ends of the arches may be employed if desired. Firing is carried on from each end of the arches, and the object of the firing is, of course, to burn the bricks, and this is accomplished most effectively by filling the arches from end to end with fire from the burners.

Due to the relatively large ratio of escape openings between bricks to the volume defined by the arch, the burning is much more rapid and satisfactory and results in less slagging or melting of the bricks in the arches than has been thought possible prior to my invention.

While preferably open clamp kilns are employed in this method of burning brick, and I shall describe a specific embodiment em-

ploying the same, there are certain features of my invention which may be employed in the manufacture of brick regardless of the kind of kiln employed.

Now in order to acquaint those skilled in the art with the manner of practicing my process, I shall describe in connection with the accompanying drawing a typical layout of the kiln.

Fig. 1 is a top plan view of a kiln with certain of the layers removed to show the manner of building the same, and showing the burners in position.

Fig. 2 is a top plan view of a fragmentary part of the kiln, showing the manner of closing up the arches between unit piles, as is performed in the center of the kiln shown in Fig. 1.

Fig. 3 is a section through a part of the kiln illustrating diagrammatically the manner of making up the kiln; and

Fig. 4 is a plan view of a modified or alternative method of making up the arches from solid unit piles of brick.

According to a well known method of making the green brick, the clay is taken from the pit, tempered, pugged and squirted through a die of single or multiple form onto a cutting table where the longitudinally extruding stream of clay is cut into brick lengths. From thence the green bricks go onto a hacking table, which is generally a belt traveling at a rate of speed greater than the rate of speed at which the clay is extruded from the brick machine, so that the bricks will be separated from each other a short space as they come to the men who take the bricks from the hacking table and pile them upon the transfer or dryer car.

The car is run alongside the hacking table and the workmen pile the brick onto the car in a suitable manner to form 2 pile having an arch extending therethrough.

After the car has been filled it is then passed on and pushed into the dryers where the bricks are subjected to hot gases for drying. After the car passes through the dryer the pile of brick is removed therefrom by a suitable fork and transferred to the kiln.

The fork is carried by the crane mounted in

an overhead position, as indicated in dotted lines in Fig. 1 at 69, the fork being suitably connected to the car 70 which is adapted to move longitudinally of the crane 69 and transversely to the length of the kiln. The overhead crane 69 travels on the overhead longitudinal tracks 71, 72 mounted on top of the posts 73 and 74 placed at the sides of the kiln. These posts also preferably support a suitable roof. 5 The crane 69 traveling on the tracks 71 and 72 longitudinally has the crane car and hoisting mechanism 70 connected to the fork so that the fork may be brought to any position within the kiln space, and may be turned 10 into any angular position desired.

In piling the brick into the kiln the unit piles with transverse arches in them are set upon the kiln floor, as shown in Fig. 1. First a unit pile such as 75 is set at one corner of 20 the kiln with the longitudinal axis of the pile extending longitudinally of the kiln floor and with the arches 30 and 31, which are formed therein, disposed transversely of the kiln floor. Thereupon a series of unit piles 25 such as 76, 77 and 78 are set upon the floor in contact with each other and all with their arches in alinement. Likewise upon the opposite side of the kiln floor and beginning at one corner there will be placed a similar 30 series of unit piles beginning at the outer end and set inwardly towards the center. The reason for setting in this manner is because the track 71, 72 for the crane 69 does not permit the crane car 70 and hence the fork to 35 be carried beyond the line of the track on either side, and hence to fill the entire kiln floor as full as possible it is necessary to start piling at the outer edge and pile inwardly. In the instance shown in Fig. 1 there are 40 four unit piles 75, 76, 77 and 78 on the left hand side, and likewise there are four unit piles on the right hand side, leaving a space 45 between them substantially ten brick-lengths wide.

This space is necessary to permit withdrawal of the fork from the innermost unit pile after it is set. This center space is then filled with solid unit piles, that is, unit piles having no arches formed therein when the 50 bricks are hacked onto the car. For forming the unit piles placed in this center space, suitable cars are employed, and solid unit piles are hacked onto the cars, dried, compacted, lifted with the fork and deposited in the center. The outermost pile in the center part of the lowermost layer of the kiln indicated at 80 is of only two brick-lengths in thickness, and this half unit pile 80 is set with its innermost edge in line with the adjacent edge of the arch 30 and with its outermost edge in line with the edges of the tunneled piles 75, 76, 77 and 78, and like tunneled piles on the right hand side as viewed in Fig. 1.

55 The next unit pile 81 which is put in the

center space between the tunneled piles, is of four brick-lengths in horizontal thickness, and so likewise are the remainder of the piles 82, 83, etc.

After the central piles such as 80, 81, 82 etc. are set into place, workmen with extra dried bricks turn the arches by the following operation, as illustrated in Fig. 2, that is to say, a layer of brick on edge is projected out transversely overhanging the space 84 between the two piles 80 and 81, this space between the piles 84 being in alinement with the arch 30.

Likewise from the pile 81 a row of bricks on edge is projected out transversely over the space 84. These bricks such as indicated at 85 and 86 on opposite sides of the space 84, extend outwardly an amount substantially equal to the thickness of a brick, and then a row of brick as indicated at 86 arranged end to end is laid back of the bricks 84. A similar row of bricks 87 end to end is set back of the bricks 86 to fill in the space which is left by the advance of the bricks 86 out over the edge of the pile.

In the lower right hand corner of Fig. 2 the operation of jetting these bricks out in order to turn the arches is shown in process. That is to say, the bricks 88 and 89 are shown as pulled out from the position formerly occupied by them, and bricks 90 and 91 as being placed back of the bricks 88 and 89. In this manner arches are formed as continuations of the arches 30 and 31 in the unit piles 75, 76, 77, and 78 and so on entirely through the bottom layer of unit piles in the kiln. In this manner the entire lower layer of the kiln is completed with arches running transversely thereacross. It will be noticed that the space between piles such as 80, 81 or 81, 82 and the like are not completely closed over in the lower layer, but that a space as shown in Figs. 1 and 2 is left in the topmost tier of bricks of the unit piles 80, 81 etc. When the next layer of unit piles is placed on top of the lowermost layer or tier of piles, these unit piles above the lowermost layer or tier are all solid unit piles. The pickup bricks of the solid piles span the space remaining between the piles such as 80, 81, 82 and the like, and complete the arch thereby.

The unit piles of the second layer or tier in the kiln are indicated at 93, and they may be set in any desired position so long as they bridge over the arches between piles 80, 81, 82, etc. Thereafter additional layers or tiers of unit piles of brick without arches, as indicated at 94, are set in place in any desired or usual manner to bring the kiln by successive layers or tiers to the desired height.

Thereafter the outside of the kiln is scoved as, for example, by piling a single layer of burned brick or brick stacks around the outside of the kiln except in line with the arches, and daubing the same with a suitable sealing

material which may be clay and brick dust. The outer layers of the kiln may have powdered coal incorporated therein to assist in making up the loss of heat due to radiation, as is well known in the art. Dog houses may be built out from the arches to receive the burners indicated at 95 and 96 at opposite ends of the arches so as to bring the flame from these burners in contact with the outermost layers of the brick of the kiln. The burners 95 and 96 are supplied with suitable fuel, for example, oil and steam or oil and air, as by means of a pair of manifolds 97 and 98 running along the kiln shed. Suitable branches from each of the pipes 97, 98 extend to the burners where valves are provided for the control of the relative proportion and for the total quantity. In burning the brick the burner endeavors to keep the arch filled from end to end with hot gases or products of combustion, which is termed fire, so that the entire bottom of the arch may, when the burning has progressed to the point of getting the lower layers hot, be subjected to full fire and the kiln then burned rapidly.

Usually it takes a progressive heating along the arches to get the bottom layers hot, and it is to be observed that with the single brick-length arches of my invention it is much easier to get the bricks hot with progressive burning from the outside towards the center than has been the case heretofore where arches are of a width greater than a brick-length. As a result the fire may be made to penetrate the lower layers of the kiln more rapidly than has heretofore been possible, and the saving in time of burning is of great importance. Whereas it has taken about 76 hours heretofore to burn a kiln of brick set with arches of the usual size, it is now possible with a kiln of my invention to reduce the burning time to about 48 hours.

The saving in labor by having the narrow arches is also of great importance. While I use a greater number of arches, that is, in a kiln of approximately one million bricks, it was customary previous to my invention to provide substantially twenty-five arches. According to my present invention I employ about thirty arches, but because of the much smaller number of bricks to be set by hand, several workmen may be dispensed with. It was previously necessary in setting the arches for the workmen to handle about four thousand bricks to the arch, while by my invention it is necessary to handle only about one hundred bricks for each arch where the arches are constructed as shown in Figs. 1 and 2.

As an alternative form of making the single brick-length arch, I may employ only solid piles as at the center of the kiln shown in Figs. 1 and 2, and construct the arches by setting the piles all transversely of the floor, as indicated in Fig. 4 in the lowermost course of

the kiln, separating the solid piles such as 100, 101 and 102 by spaces for arches, which spaces are indicated at 103 and 104 in Fig. 4 of a single brick-length in width.

Then the turning of the arches by jetting out the bricks is the same as shown in Fig. 2. Thereafter the second layer is set as shown in Fig. 3, and so on up through the rest of the kiln. In this alternative form of setting the lowermost layers it is not necessary to pre-form the arches in the unit piles.

While I have shown in Fig. 1 the two methods of forming the arches in combination, it is to be understood that either method may be practiced alone if desired, but in the event that the preformed arches are employed throughout the lowermost layer of the kiln, space must be provided along one side of the kiln for withdrawing the fork. This is possible in many installations where there is a loading shed alongside of the kiln floor and the crane is employed to span both the kiln floor and the loading space.

I do not intend to be limited to the details shown and described.

I claim:

1. The process of building an open clamp kiln which comprises placing a series of unit piles of unburned bricks on the floor of the kiln with spaces substantially a brick-length in width between successive piles of the series, then sliding the bricks at the top of the piles outwardly so that they extend out partially across the spaces, filling in the spaces in the top spaces of the piles made vacant by the change of position of the extended brick, and then placing a second series of unit piles of unburned bricks on top of the first named series so as to close the tops of the arches partially formed by the extending brick.

2. The process of building an open clamp kiln which comprises placing transversely of the floor of a kiln a series of rows of unit piles of unburned bricks with spaces substantially a brick-length in width between successive rows, then changing the position of the bricks at the tops of the piles along said rows so that such bricks extend out partially across the spaces, then placing on top of said piles and said partially closed arches a solid layer of unit piles of green bricks serving to complete the closure of said arches.

3. The process of building an open clamp kiln which comprises placing transversely of the floor of the kiln a series of rows of unit piles of unburned bricks with spaces between successive rows, then changing the position of the bricks of the top layer only along said spaces so that such bricks extend out over the spaces less than a half brick-length, filling in the spaces in the top spaces of the unit piles made vacant by the change of position of the outwardly extended bricks, and then placing on top of said piles and the partially closed arches between the piles a solid layer of unit

piles, the successive spaces between the rows being of such a width that the superposed unit piles serve to complete the closure of said arches.

5. The process of building an open clamp kiln which comprises placing a series of unit piles of unburned bricks on the floor of the kiln with spaces substantially a brick-length in width between successive piles of the series, then changing the position of the bricks at the top of the piles so that such bricks extend out partially across the spaces, and then placing a second series of unit piles of unburned bricks on top of the first named series so as to close the tops of the arches partially formed by the extending brick.

6. The process of building an open clamp kiln which comprises placing a series of unit piles of green brick on the floor of the kiln with spaces substantially a brick-length in width between successive piles of the series, then changing the position of the top layer of bricks only at each side of each of the spaces so that they extend out partially across the spaces, then placing a row of bricks end to end back of the bricks so extended out and then placing a second series of unit piles of unburned bricks on top of the first named series so as to close the tops of the arches partially formed by the extending brick.

In witness whereof I hereunto set my hand this 24th day of May, 1928.

ARTHUR J. THERRIEN.
